UNITED STATES PATENT OFFICE.

GEORGE W. SHOEMAKER, OF DALTON, PENNSYLVANIA.

WASHBOARD.

1,353,792.

Specification of Letters Patent. Patented Sept. 21, 1920.

Application filed December 30, 1919. Serial No. 348,835.

To all whom it may concern:

Be it known that I, GEORGE W. SHOEMAKER, a citizen of the United States, residing at Dalton, in the county of Lackawanna and State of Pennsylvania, have invented a new and useful Washboard, of which the following is a specification.

This invention relates to washboards, one of its objects being to provide means whereby a cake of soap held in the washboard can be fed outwardly so that, as the fabrics are worked back and forth over the wash board they will rub over the cake of soap.

Another object is to provide means whereby the cake of soap can be adjusted readily and held in any position to which it may be adjusted, there being means for firmly gripping a cake of soap of any size prior to or while being adjusted.

Another object is to provide a structure of this character which is simple durable and compact and can be manipulated readily.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a front elevation of a portion of a washboard having the present improvements combined therewith.

Fig. 2 is a central longitudinal section through the complete board.

Fig. 3 is a plan view.

Fig. 4 is a section on line 4—4, Fig. 2.

Fig. 5 is an enlarged section through the soap gripping means.

Referring to the figures by characters of reference 1 designates the side strips of the washboard connected by a lower cross strip 2, a board 3 and a top strip 4. The board 3 is provided with the usual rubbing surface 4' preferably formed of corrugated metal and at the upper end of this rubbing surface an opening 5 is formed in the board to receive the soap. The upper wall of the opening is slidably engaged by a bent plate 6 which straddles said wall and slides on the

two faces of the board and extends upwardly along the outer surface of said board into a recess 7 formed in the top strip 4 and a spring 8 which is interposed between the lower portion of the plate 6 and the board 3 60 serves to hold said plate pressed downwardly within the opening 5, the downward movement of the plate being limited by a lug 9 extending inwardly from the upper portion of the plate as shown particularly 65 in Fig. 5 so that the parts are thus held assembled and the plate cannot move downwardly such a distance as to become disengaged from the board 3. It is to be understood that a slot 10 is provided in the board 70 3 at its upper end within which the lug 9 works. Obviously when a cake of soap is placed in the opening 5 the plate 6 is first pressed upwardly to allow the cake to be positioned after which said plate is released 75 and the spring 8 will clamp the soap between the lower wall of the opening 5 and the lower portion of the plate 6.

Formed within the top strip 4 at the center thereof and extending forwardly from 80 the rear edge is a slot 11 which intersects with transverse notches 12 formed in the top strip. Any one of these notches is adapted to receive the head 13 of a tongue 14 which extends upwardly from a plate 15. 85 This plate has longitudinal slots 16 for the reception of screws 17 or the like which engage a strip 18 located back of the board 3. Said strip 18 is secured at its lower end to the cross strip 2 and is flexible, it being 90 preferably formed of wood. It is to be understood that by lifting the head 13 out of engagement with the notch 12 the tongue 14 can be swung back and forth within the slot 11 thus to move the strip 18 relative to the 95 board 3, and when the strip 18 has been brought to a desired position the head 13 can be dropped into the adjacent notch 12 thus to hold the strip 18 against further movement. A block 19 is secured to the 100 strip 18 directly back of the opening 5 and is adapted to bear against the cake of soap within the opening 5 so as to feed it forwardly when the strip 18 is adjusted toward the board 3.

It will be seen that by constructing the device as described it can be formed of few parts, will securely hold the cake of soap wherever desired and will not easily get out of order.

What is claimed is:

1. The combination with a washboard having an opening therein for the reception of a cake of soap, of a strip mounted back of the board and adjustable relative thereto, soap engaging means carried by the strip, and coöoperating means upon said strip and the upper end of the washboard for holding the strip against movement relative to the opening.
2. In a washboard the combination with a board having a rubbing surface and provided with an opening for the reception of a cake of soap, of a slotted top strip having transverse notches, a strip connected to and shiftable relative to the board and having soap engaging means, and means movable with the strip and relative thereto within the slot for engagement with any one of the notches to hold the strip against movement relative to the opening.
3. The combination with a washboard having a soap receiving opening and a slotted top strip having notches, of a strip below the slotted strip and shiftable relative to the

opening, soap engaging means on said strip, a head slidably connected to said strip and shiftable within the slot, said head being movable into any one of the notches to hold the strip against movement relative to the opening.

4. The combination with a washboard having a soap receiving opening, of a slotted top strip having notches therein, a strip shiftable relative to the opening and below the top strip, soap engaging means carried thereby, a tongue slidably connected to and movable with said last named strip and shiftable within the slot, and a head upon the tongue and shiftable into any one of the notches to hold the movable strip against shifting relative to the opening.

In testimony that I claim the foregoing as my own, I have hereto affixed my signature in the presence of two witnesses.

GEORGE W. SHOEMAKER.
